Primary Examiner — Samantha Wood*Assistant Examiner* — Vanessa Martinez(74) *Attorney, Agent, or Firm* — Aasheesh V. Shravah;
Culhane Meadows PLLC(57) **CLAIM**

The ornamental design for a circular light, as shown and described.

DESCRIPTION

FIG. 1 is a front perspective view of a circular light that is provided within a holder;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof;

FIG. 7 is a bottom plan view thereof; and,

FIG. 8 is a rear perspective view thereof.

The broken lines shown in the figures depict portions of the circular light that form no part of the claimed design.

1 Claim, 8 Drawing Sheets# US D1,030,111 S
